MULTIPLE POLE PLUG

William P. Herman, Pawtucket, R. I.

Application October 8, 1938, Serial No. 234,023

4 Claims. (Cl. 173—361)

This application is a continuation in part of the applicant's copending application Serial No. 73,901, filed April 11, 1936, now Patent No. 2,191,385, dated February 20, 1940.

My present invention relates to contact plugs and more particularly to a multiple pole plug.

The principal object of the present invention is to provide a multiple pole plug having an integral, one-piece, plug body of resilient material in which the contact blades are self-anchored.

Another object of the present invention is to provide a multiple plug construction in which the cord and blade can be assembled outside of the plug body.

A further object of the present invention is to provide a multiple plug in which the cord, blade, and plug body are so assembled that they will withstand heavy use and great strain.

An additional object is to provide a plug body having the above advantages, which is easy and economical to manufacture and to assemble.

Another object of the present invention is to provide a multiple plug suitable for assembly by means of an apparatus of the type described in my copending application Serial No. 99,848 entitled Connector plug assembly apparatus filed September 8, 1936, now Patent No. 2,198,966, dated April 30, 1940.

With the above and other advantageous features in view, my invention consists of a novel method of manufacture and assembly and a novel arrangement of parts more fully disclosed in the detailed description following, in conjunction with the accompanying drawings, and more specifically defined in the claims appended hereto.

In the drawings,

Fig. 1 is a front view of a completely assembled range plug embodying my invention;

Fig. 2 is a side view thereof;

Fig. 3 is a rear view thereof, the cover being removed;

Fig. 4 is a section taken along line 4—4 of Fig. 1;

Fig. 5 is a plan view of the cover;

Fig. 6 is an edge view thereof;

Fig. 7 is a perspective view of a contact blade;

Fig. 8 is a plan view of the blade and cord assembly;

Fig. 9 is a vertical section of the plug body with the cable inserted and the blade ready for assembly;

Fig. 10 is a sectional view of another form of my invention;

Fig. 11 is a front view thereof;

Fig. 12 is a perspective view of the cord and

blade assembly used for the form shown in Figs. 10 and 11; and

Fig. 13 is a section taken along line 13—13 of Fig. 10.

While the present invention can readily be applied to any type of multiple pole plug, for purposes of illustration only, I have herein described and shown the invention as applied to a three pole range plug.

Referring in detail to the drawings illustrating my invention, the numeral 10 generally designates the plug body, which is made of suitable insulating material, preferably resilient rubber, which is provided with a neck 11 adapted to hold the electrical cord or cable. The plug body may be of any suitable size and shape, but is preferably of diamond shape as shown in Fig. 1, and the neck 11 preferably extends from one corner of said plug body. The front of the plug body is preferably provided with three circular bosses 12, 13, and 14 arranged as shown in Fig. 1. Extending vertically through the upper circular portion 12 is a slot 15 to receive the contact blade 16, and extending through the lower circular portions 13 and 14 respectively are angularly disposed slots 17 and 18 for the contact blades 19 and 20. The spacing of the slots and blades shown in Fig. 1 is standard; the upper blade 16 is slightly longer than the lower blades and is straight, as illustrated, to form the ground connection, and the lower blades are shorter than the upper blade and have ridges 21 adjacent the tips thereof for providing a firm frictional electrical contact with the usual socket connection.

The body portion 10 of the plug is provided (Figs. 3 and 4) with a cut out housing 22 communicating with the neck 11 and forming the cable passageway, and has converging grooves 23, 24, and 25 which respectively extend from the rear of the slots 15, 17 and 18 to the housing 22.

To facilitate assembly of the type of plug shown in Figs. 1 to 4 inclusive, the back of the plug body is preferably open, a cover 26 being provided and having a groove 27 and an abutting portion 28 extending around the periphery thereof, the cover being adapted to lock into the back of the plug body 10, the groove 27 receiving the extended lip of the plug body opening 29 and the abutment 28 extending into a groove 30 around the inner edge of the plug body.

The plug body 10 is preferably molded of resilient rubber or other suitable material in the manner shown and described in my application Serial No. 90,042, entitled Method of making contact plugs, filed July 11, 1936. With this con-

struction, the slots 15, 17, and 18 each have a substantially wide slot portion 31, shoulders 32, a restricted slot area 33, shoulders 34, and another substantially wide slot portion 35 which communicates with the grooves 23, 24, and 25 respectively. The widths of the slots are substantially identical with the widths of the contact blades to be used in the slots, so that the blades can set firmly within the slots without distorting the plug body, the shoulder portions 32 and 34 cooperating with and interlocking with corresponding shoulders on the contact blades to positively lock the contact blades within the plug body.

This cooperation engagement between the contact blade and the shoulder portions in the plug body is more fully described in my copending applications Serial Nos. 22,506 and 73,901, entitled respectively Contact plug and Contact plugs, filed May 21, 1935, and April 11, 1936, now Patents Nos. 2,191,384 and 2,191,385 respectively, dated February 20, 1940, in which the efficacy and strength of this type of construction are described.

While any suitable contact blade may be used having anchoring means such as struck up lugs or the like, I prefer to use the blade construction shown in Fig. 7. In this construction, the contact blade consists of a main body portion 36 having an opening 37 for engagement by the pull arms of the assembly machine, and a shoulder portion 38, a substantially narrower body portion 39, terminating in a shoulder portion 40, and a head 41. The head 41 receives the electrical cord connection and is split in three as shown in Fig. 7, the two outer portions forming prongs slightly curved forwardly, and the middle portion curved in the opposite direction so that when an electrical cord connection is placed therebetween, as shown in dotted lines in Fig. 7, it is effectively gripped and held by the contact blade. For further security, the electrical cord connection may be spot welded to the central prong as shown at 41a in Fig. 4.

As shown in Figs. 1 to 4, the electrical cord connection is preferably at right angles to the contact blade. This assembly is shown in Fig. 8, wherein each contact blade is attached to its electrical cord connection in the manner just described. In assembly, the contact blades are first fixed to the electrical cord connection and the electrical cord is pulled through from the back of the plug body through the neck 11 as shown in Fig. 9. To take up the strain on the cable, the neck 11 is preferably $\frac{1}{8}$ of an inch less in diameter than the cable. By using a machine of the type shown and described in application Serial No. 99,848, entitled Connector plug assembly apparatus, filed September 8, 1936, the contact blades may be pulled into their respective slots and effectively anchored therein as shown in Fig. 4.

In assembled position the contact blades and cord take the position shown in Fig. 3, with the individual electrical cord wires leading to each contact blade flatly disposed in their respective grooves. The insulating material between the grooves separates the bare ends of the cord lead wires and prevents high amperage arcing. The cover 25 is then mounted into the back to close the connection chamber and to prevent short-circuiting by insertion of foreign matter or by wetting.

The construction just described is adapted for use in places where the electrical cord is pref-

erably at substantially right angles to the contact blade. However, it is more advantageous in different types of installations to have the electrical cord cable in line with the contact blade. For this I have devised the construction shown in Figs. 10 to 13 inclusive.

Referring to Figs. 10 and 11, the plug body 42 is preferably circular and comprises a flat front portion 43 having bosses 44 corresponding to similar portions in the form shown in Fig. 1, and having slots 45 and blades 46 similarly disposed therein. The plug body 42 is preferably tapered towards the rear as indicated at 47, and ends in a rim or lip 48.

15 A cable opening 49 extends through the rear portion of the plug body 42 and opens into a cable receiving chamber 50 which has three diverging passageways 51 connecting with the slots 45 in which the contact blades are anchored. As 20 in the previous form, the cable opening 49 is preferably $\frac{1}{8}$ of an inch less in diameter than the cable. This will firmly anchor the cable against strains as provided by the underwriters' tests.

25 The dielectric material between the diverging passageways 51 forms a plurality of conical baffles effectively separating the bare ends of the cable wires and preventing high amperage arcing and short circuiting.

30 Referring to Fig. 12, I prefer to use a modified form of contact blade as shown therein, the rear portion of the contact blade being provided with a U-shaped cut out into which the cord lead wire can be anchored and spot welded as at 52. The contact blades are preferably spot welded to the cord lead wire in line therewith so that, see Fig. 10, when the contact blade, cord, and plug body are assembled, the cable will extend out of the plug body in line with the contact blade.

35 40 The form shown in Figs. 10 to 13 inclusive is assembled on the assembly machine hereinbefore referred to, but there is no preliminary insertion of the cables, as is required for the form shown in Figs. 1 to 4 inclusive. The plug body is merely placed into the machine and the blade and cord lead wire are pulled into the slots, whereby the corresponding shoulders and abutments on the contact blades and the slots will effectively lock the blades in the plug body.

45 50 The form shown in Figs. 10 and 11 also corresponds to standard multiple plug contact blades, the upper blade being straight and slightly longer than the two lower blades and the two lower blades being disposed at opposite angles and having the usual ridges near the tips thereof.

55 60 The plugs in both frames can obviously be made with 4, 5, or any number of poles, and as hereinbefore described, are simple in construction and easy and economical to manufacture and assemble. They can be made of resilient materials such as soft rubber and will withstand hard strain, pulls, and knocks, and will effectively pass all tests necessary for strength, dielectric properties, and short circuiting, required for this type of article.

65 While I have described specific constructional embodiments of my invention, and specific methods for assembly, it is obvious that these are merely illustrative, and that changes in the size and shape of the parts, the materials used for the parts, their relative arrangement, and the assembly methods followed, may be made to suit the requirements for different plug designs, without departing from the spirit and the scope of

the invention as defined in the appended claims.

I claim:

1. In a plug construction, a one-piece plug body of resilient material having a cable opening through one end thereof and three grooves in the upper surface for individual leads extending divergently from said cable opening, said body having three rectangular transverse blade passageways terminating in the said grooves and adapted to receive flat rectangular contact blades having restricted portions adjacent their head ends, said passageways each having opposed constrictions intermediate the passageway ends adapted to seat in the blade head end restricted portions.

2. In combination, a one-piece plug body of resilient material having a cable opening through one end thereof and three grooves in the upper surface for individual leads extending divergently from said cable opening, said body having three rectangular transverse blade passageways terminating in the said grooves and adapted to receive flat rectangular contact blades therein, flat, rectangular, contact blades having head ends and seated in said passageways, said blades having restricted portions adjacent their head ends, said passageways each having opposed constrictions intermediate the passageway ends adapted to seat in the blade head end restricted portions,

and a cable in said cable opening having leads in said grooves secured to the blade head ends.

3. In a plug construction, a one-piece plug body of resilient material having a cable opening through one end thereof and three grooves for individual cord leads extending divergently from said cable opening, said grooves terminating in three spaced rectangular blade passageways adapted to receive flat rectangular contact blades having restricted portions adjacent their head ends, each passageway having opposed constrictions intermediate the passageway ends adapted to seat in the blade head end restricted portions.

4. In combination, a one-piece plug body of resilient material having a cable opening through one end thereof and three grooves for individual cord leads extending divergently from said cable opening, said grooves terminating in three spaced rectangular blade passageways adapted to receive flat rectangular contact blades therein, flat, rectangular, contact blades having head ends and seated in said passageways, said blades having restricted portions adjacent their head ends, each passageway having opposed constrictions intermediate the passageway ends adapted to seat in the blade head end restricted portions, and a cable in said cable opening having leads in said grooves secured to the blade head ends.

WILLIAM P. HERMAN.
